(57) **CLAIM**

The ornamental design for an abdominal support apparatus, as shown and described.

DESCRIPTION

FIG. 1 is a front perspective view of an abdominal support apparatus of the present invention.

FIG. 2 is a rear perspective view of the abdominal support apparatus of FIG. 1.

FIG. 3 is a side elevation view of the abdominal support apparatus of FIG. 1.

FIG. 4 is a top plan view of the abdominal support apparatus of FIG. 1.

FIG. 5 is a bottom plan view of the abdominal support apparatus of FIG. 1.

FIG. 6 is a front elevation view of the abdominal support apparatus of FIG. 1; and,

FIG. 7 is a rear elevation view of the abdominal support apparatus of FIG. 1.
